COMBINED ROOM AIR FRESHENER AND DEODORIZER

Morris Friedman, New York, N.Y., and Andrey V. Mackey, Ambler, Pa., assignors to Minerware, Inc., New York, N.Y., a corporation of New York, and H.M.S. Associates Co., Willow Grove, Pa., a corporation of Pennsylvania

Filed Apr. 17, 1963, Ser. No. 74,480

Term of patent 3½ years

(Cl. D16—2)

FIG. 1 is a front elevation view of a combined room air freshener and deodorizer showing our new design;

FIG. 2 is a side elevational view, partially broken away and in section to better illustrate the configuration of the container element; and

FIG. 3 is a top plan view of the combined room air freshener and deodorizer of FIG. 1.

The rear portion of the container element not disclosed in FIGS. 2 and 3 is substantially flat and plain.

We claim:

The ornamental design for a combined room air freshener and deodorizer, substantially as shown and described.
